UNITED STATES PATENT OFFICE.

HENRY E. BILLMAN AND LEO R. MANN, OF ST. LOUIS, MISSOURI.

SWITCH-STAND.

1,120,365.

Specification of Letters Patent.

Patented Dec. 8, 1914.

Application filed June 29, 1914. Serial No. 847,803.

To all whom it may concern:

Be it known that we, HENRY E. BILLMAN and LEO R. MANN, citizens of the United States, residing at the city of St. Louis, 5 State of Missouri, have invented certain new and useful Improvements in Switch-Stands, of which the following is a specification.

This invention relates to improvements in 10 switch-stands and relates particularly to improvements in the switch-stand of our invention disclosed in our application for patent filed in the United States Patent Office June 16, 1913, Serial No. 773,846, and has 15 for its object to provide a switch-stand of cheap and simple construction and of few parts, easily assembled, of great durability and strength, and positive in operation.

Further, the present invention resides in 20 the novel features of construction and arrangement of parts hereinafter more fully described and pointed out in the claims.

In the accompanying drawings forming 25 part of this specification, in which like numbers of reference denote like parts wherever they occur, Figure 1 is a perspective view, looking from the track, of the switch-stand embodying this invention; Fig. 2 is a plan view looking down upon the switch-stand; 30 Fig. 3 is a side elevation of Fig. 2 looking from the track.

A base 1 comprising in one piece the base-plate 2, a pair of standards 3 (one standard preferably adjacent to each end of base 1 35 at the side thereof farthest from the track), a pillow-block intermediate said two standards (preferably on the same side of base 1 as standards 3), guides 5 intermediate the sides of base 1, bearing 6 preferably at the 40 side adjacent to the track (not shown), and underhung bearing 7 extending downwardly beneath base-plate 2 preferably adjacent to bearing 6.

Base-plate 2 is adapted to rest on ties 8 45 in the usual manner and is secured thereto by means of spikes or the like (not shown) through openings 9 in said base-plate and, also, preferably at notches 10 in the outer edges of said base-plate, there being as many 50 such openings and notches as may be desired. Preferably one or more openings 11 provided in base-plate 2 between ties 8 permit water to drain out of inclosures formed upon the said base-plate by the protruding 55 edges 12 of the web of the base 1.

A shaft 13 is supported in a bearing 14 in pillow-block 4, said shaft being retained in said bearing by cap 15, which is fastened to said pillow-block by bolts 16 or other suitable means. One end of said shaft 13 has 60 the throwing lever 17 secured thereto by any suitable means, the free end of said throwing lever preferably bearing a weight 18 to facilitate the throwing of the switch-points (not shown). The throwing lever is arranged to move through substantially 180 degrees in a vertical plane and is positively limited in such movement by the pair of standards 3. The standards 3 have their upper ends bifurcated so that, when the throwing lever 17 occupies substantially a horizontal position (best seen in Fig. 1), said lever will rest upon a standard 3 and will extend between prongs 19 of the latter, one of said prongs being preferably longer than 65 the other and having an opening 20 for the reception of a hasp or padlock 21 or other suitable device for locking the throwing lever in its horizontal position. The other end of said shaft 13 bears one end of a crank 22, the other end of said crank bearing a crank-pin 23 with an anti-friction roller 24 revolvably mounted thereon, said anti-friction roller being held on said pin by cotter-pin 25 or other suitable means. Crank 22 70 preferably extends in the opposite direction from throwing lever 17 so that, when the latter is moved through an arc of substantially 180 degrees above the horizontal plane 75 through the axis of shaft 13, the former will 70 be moved through an arc of substantially 180 degrees below said plane. Crank-pin 23 receives a member 26, said member having a vertical slot 27 through which crank-pin 23 80 extends. The member 26 bears a pair of 85 oppositely-extending arms 28 each of which is provided with an elongated opening 29 running lengthwise the arm, each opening having a pair of lugs 30 and 31, one, 30, preferably located in the upper portion of 90 said opening farthest from said member 26 and the other, 31, preferably located in the lower portion nearest said member 26, each of said arms preferably bearing a perforated extension 32 at its free end, each of 95 said perforated extensions being adapted to receive and hold attached a member (not shown in the drawings and which member may be either a rod or a flexible element) so that power may be obtained from either of 100 105 110

said arms to operate a distant signal, cross-over switch, derail, frog, etc. (not shown in the drawings).

The arms 28 extend along base plate 2 and are slidably supported thereon by guides 5, which guides are preferably bifurcated for the purpose of receiving said arms as best shown in Fig. 1, and each bifurcated portion being preferably strengthened by 10 buttress-like webs 33, and, moreover, each of said guides 5 being provided with openings 34 transverse the direction of said bifurcations and transverse the direction of the arms 28 in their extension along base-plate 1, which opening 34 is adapted to communicate with opening 29. A cotter-pin 35 or the like is preferably provided in an appropriate opening 36 therefor in each guide 5 at or slightly above the level of the upper 15 edge of arms 28, when said arms are slidably in place in said guides, to prevent said arms from lifting upwardly out of position in operation and to permit lugs 30 and 31 positively to perform their functions hereinafter described. The lower portion of member 26 extends through an opening (not shown) in the base-plate 2, said opening being provided to permit said member 26 with its lower portion extending through base-plate 2 to move forward and backward as arms 28 extending from said member 26 slide forward and backward in guides 5 along said base-plate, and a pin 37 borne by the lower portion of said member 26 20 (said pin having an anti-friction roller 38 revolvably mounted thereon and being provided with a cotter-pin 39 or the like for holding said anti-friction roller in place on said pin) extends through a cam slot 40 in the operating crank 41, which is rigidly mounted on vertical shaft 42 in underhung bearing 7 below base-plate 2, said crank being so mounted preferably between bosses 43 provided as part of said bearing 7. Vertical shaft 42 is rotatably mounted in bearing 7 and extends upwardly therefrom through bearing 6, which is located immediately above bearing 7, and shaft 42 bears near its upper end the usual target vanes 44 and terminates with a lamp-plug 45 to allow a signal-lamp (not shown) to be mounted thereon in the usual manner.

The cam slot 40 is preferably Y-shaped, having two branches 46 disposed at substantially a right-angle to each other, and a third branch extending radially to the pin 37 and substantially bisecting the vertical angle of the branches 46, as shown in Fig. 2. Crank 41 is pivotally attached at 47 to one 55 end of the connecting rod 48 by bolt 49 or other suitable means (Fig. 1), the other end of said connecting rod 48 being connected to the switch-points (not shown) preferably to a tie-rod (not shown) of said switch-point.

Normally, the member 26 occupies a position with crank-pin 23 and anti-friction roller 24 in the upper end of vertical slot 27 when pin 37 stands in the end of one of the branches 46 of cam slot 40 and thereby holds the operating crank 41 in such position that said branch 46 coincides with the path of movement of pin 37, with the result that the switch-points (not shown) connected to rod 48 are held locked in their set position. When it is desired to throw the switch-points, the throwing lever 17 is moved through an arc of substantially 180 degrees as hereinabove described. The branches 46 of the cam slot 40 are preferably so arranged relative to the throwing lever 17 that, when the latter is moved through the first 45 degrees of its movement, the crank 22 moves the member 26 sufficiently to cause the pin 37 to travel through and pass out of one of the branches 46 of cam slot 40 without effecting rotary movement of the operating crank 41. This movement of the member 26 merely unlocks the switch, and during the next 90 degrees of the movement of the lever 17 the crank 22 moves the member farther in the same direction and thereby causes the pin 37 to enter the radial branch of cam slot 40 and to engage one side of same, whereby said pin 37 rotates the operating crank 41 through substantially 90 degrees, with the result that said operating crank effects the positive throwing of the switch-points (not shown) through the medium of the connecting rod 48. This rotary movement of the operating crank 41 causes the vertical shaft 42 to rotate through substantially 90 degrees and thereby effects the positive setting of the target vanes 44 and signal-lamp (not shown), borne by said vertical shaft. During the last 45 degrees of the movement of the lever 17, the crank 22 moves the member 26 farther and thereby causes the pin 37 to enter the other branch 46 of the cam slot 40 and to move to the end of said branch, which branch will have been moved to a position in which it coincides with the path of movement of the pin 37. This movement of the lever 17 causes the pin 37 to lock the operating crank 41 in its new position and thereby prevents the switch-points (not shown), connected with operating crank 37 as hereinabove described, and the vertical shaft 42 from being moved until the throwing lever 17 is moved in the reverse direction through more than 45 degrees, as hereinabove described.

It will be seen that, by reason of the connecting rod 48 being directly connected to the operating crank 41 and said crank being rigidly mounted on vertical shaft 42, said vertical shaft 42, bearing target vanes 44 or signal-lamp (not shown) or both, moves synchronously with the switch-points (not

shown) and thereby causes the target vanes or signal lamp or both to indicate the exact position of said switch-points. It will be seen that this arrangement eliminates all lost motion and insures the positive throwing of the switch-points and the positive setting of the signal.

As an auxiliary means for locking the switch-points (not shown) in a set position, the following mechanism is provided. The rod 50 at an extension thereof to the track (not shown) is connected preferably with the points of the switch-tongue (not shown) in any suitable manner, and the end of said rod at the switch-stand, said end bearing an upper transverse notch 51 and a lower transverse notch 52 adapted to engage, respectively, lugs 30 and 31, is inserted through opening 34 adapted to receive same in a guide 5 and transversely through communicating elongated opening 29 of an arm 28. Notches 51 and 52 are adapted to register in the paths of movement, respectively, of corresponding lugs 30 and 31 of an arm 28 as said arm moves forward and backward through guide 5 as lever 17 is moved through an arc of 180 degrees from the position shown in Fig. 1, to the position shown in Fig. 2 or the reverse, and, when the switch-points are in set position as hereinabove described, one of said notches 51, 52 engages one of said lugs 30, 31 and through the extension of the rod 50 connected with the points of the switch-tongue (not shown) holds the point so set close up against the stop-rail (not shown) and locks same in that position thus providing a means for locking the switch-points in a set position auxiliary to the means provided by the co-operation of a slot 46 with the pin 37 and the operating crank 41 through the connecting rod 48, as hereinabove described.

The present invention simplifies in many ways the construction of the switch-stand of our invention disclosed in our application, Serial No. 773,846, above-referred to, greatly reduces the number of separate parts, provides various novel features, reduces the cost of construction by reducing the amount of machine work, lessens the labor and expense in assembling and erecting, eliminates a large number of bolts, nuts, and fitting together of parts, and provides a device certain and positive in operation. For instance, by forming the standards 3 integral with base 1, not only are the number of separate parts reduced together with their bolts and the like, but, also, the motion of lever 17 may be positively limited to an arc of 180 degrees, because the base of said standards being integral with the base of the switch-stand, the varying of the level of the ties to which said base is secured will not affect the standards to alter their adjustment relative to the limited motion of said

lever, as may be the case when each standard is a separate part and is separately spiked or bolted to separate ties, and, also, a number of bolts and the like are eliminated and the labor and expense of assembling and fitting together of parts is eliminated. Also, by constructing the pillow-block 4 integral with the base, not only is the construction simplified, the number of separate parts reduced, and the expense of assembling those parts avoided, and the like, but, also, a substantial pillow-block with a single bearing for shaft 13 is provided instead of the two bearings provided in our invention disclosed in our application, Serial No. 773,846 above-mentioned.

The base-plate 2 of the switch-stand of the present invention is substantially a flat-surface having an opening in its floor thus permitting the lower portion of member 26 to extend below said base-plate so that associated parts are located, connected, and operate below said base-plate, thus avoiding the more expensive U-shaped base disclosed in our prior application, Serial No. 773,846.

The underhung bearing 7 is a novel feature not provided for in the invention disclosed in our said prior application for patent and provides a simple and cheap means for revolvably mounting shaft 42 so that operating crank 41 may be rigidly mounted thereon below the base-plate 2 of base 1. Further, the novel features of construction and operation of an auxiliary locking device of the present invention operative through an opening in guide 5 (guides 5 being integral with the base in the present invention) by means of notches 51 and 52 on rod 50 coöperative in an opening 29 communicating with said opening in guide 5, are not shown in our invention disclosed in our said prior application. These and other novel features of construction, arrangement of parts, and of operation described in this specification are substantial advantages provided by the present invention that switch-stands of other inventions do not disclose.

Various changes in the details of construction and arrangement of parts may be made without departing from the nature and spirit of this invention.

We claim:

1. In a switch-stand, the combination with a base having integral therewith a pair of standards, a pillow-block, guiding means, and an underhung bearing, of a reciprocating member slidably mounted on said base in said guiding means, means upon said reciprocating member above said base for actuating said reciprocating member, said actuating means being mounted in said pillow-block and the motion of said actuating means being limited by said standards, a member pivoted in said underhung bearing and operated by said reciprocating member

below said base, a switch actuator, and means connecting said pivoted member and said switch actuator.

2. In a switch-stand, the combination

- 5 with a base having integral therewith a pair of standards, a pillow-block intermediate said standards, guiding means, a bearing on the upper surface of said base, and an underhung bearing below said base, of a reciprocating member slidably mounted upon said base in said guiding means, means supported in said pillow-block for actuating said reciprocating member, the motion of said actuating member being limited by said standards, a shaft revolvably mounted in said two bearings, a member borne by said shaft below said base and operated below said base by said reciprocating member, a switch actuator, and means for connecting said member borne by said shaft to said switch actuator.
- 10

3. In a switch-stand, the combination with a base having an opening therein, said base having integral therewith a pair of standards, one standard at each end of said base on the side thereof farthest from the switch, a pillow-block intermediate said standards and on the same side of said base as said standards, guiding means, a bearing 25 on the upper surface of said base at the side thereof nearest the switch, and an underhung bearing below said base depending immediately beneath said first-named bearing, said underhung bearing having two opposite bosses, of a reciprocating member slidably mounted on said base over said opening therein and in said guiding means, means supported in said pillow-block for actuating said reciprocating member, the motion of 30 said actuating member being limited by said standards, a shaft revolvably mounted in said two bearings, a member borne by said shaft below said base between said two bosses in said underhung bearing, said member being operatively connected below said base with said reciprocating member, a switch actuator, and means for connecting said member borne by said shaft to said switch actuator.
- 35

4. In combination with a pivoted member connected to the switch, a vertical member, horizontal arms on said vertical member, an elongated opening in each of said arms, a lug in the upper portion of said opening, a lug in the lower portion of said opening, rigid means to slidably support said arms, a transverse opening in said rigid means and communicating with the elongated opening of the arm supported by said rigid means, the lower end of the vertical member engaging the pivoted member to actuate and lock the latter, means connected to the upper end of the vertical member to reciprocate same, and a member connected at one end to the 65 switch, the other end having a notch in its

upper surface and a notch in its lower surface, said notched end being supported in a transverse opening in said rigid means and extending through the elongated opening in said arm, and the upper and lower notches being adapted, respectively, to engage the upper and lower lug of said elongated opening for auxiliarily locking the switch.

5. In combination with a base and a pivoted member below said base connected to a switch, a vertical member having its lower extremity engaged with the pivoted member below said base, means to mount said vertical member to enable same to slide in a straight line, rigid guiding means on said base to engage the lower portion of said vertical member above said pivoted member, and means to reciprocate said vertical member.

6. In combination with a base and a pivoted member below said base connected to a switch, a vertical member having its lower portion engaged with the pivoted member below said base, horizontal arms on said vertical member, an elongated opening in each arm, a lug in the upper portion of said opening, a lug in the lower portion of said opening, rigid means to slidably support said arms on said base, a transverse opening in said rigid means, said opening communicating with the elongated opening of the arm supported by said rigid means, means connected with the upper portion of the vertical member to reciprocate same, and an auxiliary locking device, said device consisting of a member connected to the switch-point and having a notch in the upper surface of its free end and a notch in the lower surface of said end, said end being adapted to be supported in said transverse opening and to extend through said elongated opening, the upper notch and the lower notch being adapted, respectively, to engage the corresponding upper and lower lugs in said elongated opening as the arm slides backward and forward when said vertical member is reciprocated and being adapted to lock the switch-points in a set position when said engagement of parts is effected.

7. In a switch-stand, the combination with an actuator for the switch, of a base, an L-shaped bearing depending therefrom, a member pivoted to and between said bearing and the bottom of said base and having a connection with the switch actuator, and means operatively supported by said base for actuating said pivoted member.

8. In a switch-stand, the combination with an actuator for the switch, of a base having a longitudinal slot in the bottom thereof, an underhung bearing depending therefrom, a member pivoted to and between said bearing and the bottom of said base and having a connection with the switch actuator, a vertical member reciprocatively supported on said

base and having its lower portion extending through the slot in said base and its lower extremity engaging said pivoted member to actuate same, and means for reciprocating 5 said vertical member.

9. In a switch-stand, the combination with an actuator for the switch, of a base having a longitudinal slot in the bottom thereof, an underhung bearing depending therefrom, a 10 member pivoted to and between said bearing and the bottom of said base and having a connection with the switch actuator, a vertical member having its lower portion extending through the slot in said base and its 15 lower extremity engaging said pivoted member to actuate same, a pair of horizontal arms borne by said vertical member and projecting from opposite sides thereof, guides borne by said base at or adjacent to the ends 20 of the slot therein adapted to slidably support said arms, and means for reciprocating said vertical member.

10. In a switch-stand, the combination with an actuator for the switch, of a base having a longitudinal slot in the bottom thereof, an underhung bearing depending therefrom, a member pivoted to and between said bearing and the bottom of said base and having a connection with the switch actuator, a 25 vertical member having its lower portion extending through the slot in said base and its lower extremity engaging said pivoted member to actuate same, a pair of horizontal arms borne by said vertical member and 30 projecting from opposite sides thereof, guides borne by said base at or adjacent to the ends of the slot therein adapted to slidably support said arms, means for reciprocating said vertical member, and means for retaining 35 40 said arms in said guides.

11. In a switch-stand, the combination with an actuator for the switch, of a base having a longitudinal slot in the bottom thereof, a pivoted member located below said base and 45 supported thereby and having a connection with the switch actuator, means reciproca-

tively supported on said base extending through the slot in the latter and engaging said pivoted member to actuate same, and means for actuating said reciprocating 50 means.

12. In a switch-stand, the combination with an actuator for the switch, of a base having a longitudinal slot in the bottom thereof, a pivoted member located below said base and 55 supported thereby and having a connection with the switch actuator, a vertical member having its lower portion extending through the slot in said base and its lower extremity engaging said pivoted member to actuate 60 same, a pair of horizontal arms borne by said vertical member and projecting from opposite sides thereof, each arm containing an elongated opening and bearing a pair of lugs disposed diagonally opposite each other 65 within the opening, a pair of guides borne by said base at or adjacent to the ends of the slot therein adapted to slidably support said arms, means for reciprocating said vertical member, there being transverse guide openings in said guides which communicate with the openings in said arms, and an element 70 connected to the switch and arranged to extend through the guide openings of one of said guides and, also, through the opening 75 in the arm of said vertical member supported by the latter, there being a pair of notches in the upper and lower edges of said element adapted to interlock, respectively, with the lugs in the opening of the particular arm 80 through which said element passes, thereby to lock the switch in open and closed positions.

In testimony whereof we hereunto affix our signatures in the presence of two witnesses.

HENRY E. BILLMAN.
LEO R. MANN.
